UNITED STATES PATENT OFFICE

HANS ERNST AND LESTER F. NENNINGER, OF CINCINNATI, OHIO, ASSIGNEES TO CINCINNATI GRINDERS INCORPORATED, OF CINCINNATI, OHIO, A CORPORATION OF OHIO

SPINDLE OSCILLATOR

Application filed December 9, 1926. Serial No. 153,660.

This invention relates to improvements in grinding or like machinery and has particular reference to a novel and improved mechanism for oscillating a spindle or other portion thereof.

One of the principal objects of the present invention is the provision of an hydraulic mechanism which may be satisfactorily utilized for imparting a slow reciprocating motion to a rotary member, such as the supporting spindle of a grinding wheel.

A further object of the invention is the provision of a mechanism which shall be entirely self-contained and automatically imparting movement in alternate directions to the oscillated device.

Another object of the present invention is the provision of an automatic mechanism which may be readily adjusted for different degrees of oscillatory movement from a very fine movement to one of considerable extent and in which the reversal shall at all times be positive in its operation.

An additional object of the invention is the provision of an improved fluid pressure mechanism for imparting an oscillatory movement to a spindle or like structure, in combination with improved pressure operated means for controlling the reversal of direction of movement of the parts.

Other objects and advantages of the present invention should be readily apparent by reference to the following specification, taken in connection with the accompanying drawings, and it will be understood that we may make any modifications in the specific structural details hereinafter disclosed within the scope of the appended claims, without departing from or exceeding the spirit of the invention.

Figure 1 is a fragmentary perspective view of the invention applied to a grinding machine spindle.

Figure 2 is a vertical sectional view through the oscillating mechanism.

Figure 3 is a sectional view on the line 3-3 of Figure 2.

Figure 4 is a sectional view of the control valve mechanism, and

Figure 5 is a fragmentary view of the combined detent and valve actuator.

In the drawings in which similar characters of reference denote corresponding parts throughout the several views the letter A designates the journal of a grinding machine containing the bearings B for the grinding wheel spindle C, which bears on one end the grinding wheel D. These parts it will be understood have been conventionally selected for purposes of illustration and application of the present invention, since the unit hereinafter described may be applied to any other desired form of mechanism in which a relative oscillation of parts is desired.

Secured to the journal bracket A as by bolts 10 is the base flange 11 of the oscillator housing 12. The member 12 supports a thrust bearing 13 for engagement with a shoulder 14 on the spindle C, so that when the spindle is positively urged toward the right as view in Figure 2, and held in this direction the end thrust will be taken up by the bearing aforesaid and undue frictional retardation due to pressure holding the spindle toward the right will be eliminated. It will be understood that the housing member as an entirety is formed of several separable parts, including the portion which has been particularly designated by the reference character 12, a cylindrical portion 15 and an end or cap plate portion 16, these several parts being secured together as a unit through the medium of the clamp bolts 17. The portion 15 is chambered as indicated at 18 and 19 for example, to provide a circumscribing reservoir for the oil or other fluid used as the power transmitting or actuating medium. A cap plate 20 provided with a filler plug 21 affords ready access to this chamber for cleaning purposes or the like and for supply of the necessary fluid.

Encircling the extension 22 of the grinding wheel spindle in spaced relation thereto, is the sleeve 23 having an internal annular rib 24. Disposed on each side of the rib 24 are the thrust bearings 25 and 26, the thrust bearing 25 being disposed between flange 24 and shoulder 27 of the spindle extension 22 tak-

ing up thrust imparted to the spindle through movement of the sleeve toward the left, while the thrust bearing 26 is disposed between the rib and the clamp nuts 28 on the end of the extension 22 and takes up the thrust tending 5 to move the spindle toward the right. This sleeve is provided with a peripheral flange 29 at its inner end, slidably supported by the housing member 12. Mounted upon this sleeve is the piston proper 30, which will later 10 be described in detail. A spacer sleeve 31 is disposed intermediate the piston and end of the sleeve 23, the several parts being clamped together to move as a unit by the hollow nut 32 engaged on the threaded portion 33 of the sleeve. A stud screw 34, see Figure 3, carried by the portion 15 has its end slidably received in keyway 35 in the piston 30 to lock 15 the piston member against rotative movement, while permitting of its longitudinal 20 sliding or oscillation.

It will be noted that piston 30 is in direct sliding engagement at its ends with the inner wall of member 15, but has a central annular 25 groove as at 41 in communication with the fluid reservoir 18. The piston is thus reciprocable between wall 42 of member 12 and wall 36 of member 16. Its movement within these limits, however, may be varied and limited by rotative adjustment of nut 37 on the terminal threaded portion 38 of spacer 31, inasmuch as contact between nut 37 and seat 39 on cap member 16 limits the movement of the piston and associate parts toward the 35 left. A locking device such as a slot and screw indicated at 40 in Figure 2, secures nut 37 in desired adjusted position by pinching the slot in the nut against contained threads on the spacing sleeves.

40 The oscillation of the piston and thus of the spindle is intended to be effected through the utilization of a self-contained pressure creating mechanism utilizing the fluid from the reservoir 18 for actuating purposes. Primarily, this mechanism comprises a pair of 45 plunger pumps 43 which are centrally slidably supported in the pump cylinders 44 of the piston 30 and associate parts and have their inner ends projecting into engagement with the double lobed cam 45, preferably formed 50 integral with or secured upon the spindle extension 22. Springs 46 serve to urge the plungers inward, while rotation of the cam 45 with the grinding machine spindle causes 55 the actuating or pressure stroke of the plunger. It will be noted that by having oppositely disposed plungers and a symmetrical cam the two plungers will at all times oppose each other in their pressure and suction 60 strokes, thus minimizing the possibility of vibratory effect on the spindle or other mechanism.

The operation of the pump pressure system will perhaps be best understood by reference to Figure 2, showing the piston and

pump plunger mechanism, and Figure 4 showing the valve controlling the flow of fluid under pressure, together with a diagrammatic illustration of the conveyor lines for said fluid. From these it will be noted that the reservoir 18-19 communicates through 70 conduit 46' with the distributor groove 47 in the inner face of piston 30. From said groove fluid may be drawn on the suction stroke as through conduits 48 controlled by 75 the automatic ball or check valves 49. On the completion stroke the fluid just drawn in will be forced through passage 50 and past check valve 51 into the conduit 52 and annular distributor passage 53 to the valve casing 54. It will be noted that the line 53 branches into portion 53' extended to the right hand side and 53'' extending to the left hand side, these passages terminating in the annular distributor grooves 55. The valve 80 casing and contained valve it will be noted are disposed within the body of piston 30 but eccentrically disposed as respects thereto.

The valve mechanism includes a valve rod 56 having at one end a piston valve 57 and at the other the piston valve 58. Loosely 90 mounted upon the rod intermediate said valves is a combined valve and actuator member 59. The casing has the cylinder portions 60 and 61 at its ends in which the piston 95 valves slide.

When the parts are in the position indicated in Figure 4, the flow of fluid is from reservoir 19 or exhaust line 62 through the pump mechanism to line 53. Thence it passes through 53' into cylinder 61 and via chamber 63 to passage or port 64, discharging 100 to the space 65 between the end of the piston and the wall 36 of the cap plate member. This pressure will therefore tend to move the piston to the left, shifting with it the spindle to be oscillated. To retain the fluid under pressure within chamber 63 so that it may perform this work, the supplemental valve member 59 is utilized, it having a face 66 seated against the wall of the chamber to seal in the pressure. A spring pressed ball 105 detent 67 actuated by spring 68 is engaged in notch 69 of member 59 to hold same to the right. The pressure exerted by spring 68 is sufficient to resist movement of member 59 tending to release pressure in chamber 63.

As the piston moves toward the left, fluid contained in chamber 70 intermediate the opposite end of the piston 30 and the wall 42 of the oscillator casing 12 may exhaust through port 71, chamber 72 and outlet 73 to pipe 62.

However, when the piston has reached its 125 limit of movement to the left, the continued rotation of the grinding wheel spindle will build up an increasing pressure in line 53. This pressure will react against member 59 moving this member to the left and raising

the spring actuated detent 67 on rib 74. The pressure escape around the valve face 66 is sufficiently slight so that the building up of pressure in chamber 63 will be sufficient to move member 59 to the left until the ball 5 rides over the crest of the rib and into groove 75. During this movement of member 59, the valve rod 56 and piston valves have been stationary, due to the lost motion action 10 present. At the point just mentioned, however, the end of member 59 will now be in contact with piston 57 when the combined action of the pressure and the bodily forcible action of ball 67 on the inclined face of notch 75 will shift member 59 and the piston rod 56 with attached valves as a unit. This unitary shifting of the parts will move valve 57 away from pressure inlet 53" when the pressure may flow from groove 55 through 20 chamber 72 and passage or port 71 into the chamber 70, reversing the direction of movement of the piston. At the same time valve 58 will have been shifted to close pressure inlet 53' when the fluid previously forced 25 into chamber 55 may reversely flow through passage 64 and thence from chamber 63 through the main central chamber to outlet passage 62.

In the shifting movement of the parts 30 just described the member 67 serves to retain member 59 against movement in either direction until a suitable actuating pressure has been built up when the initial movement of member 59 under influence of the pressure 35 cams ball 67 upward placing an additional load or compression force on spring 68 until the high point of the central rib 74 is reached. At this point the ball moving over the crest of the rib acts as a load and fire valve operating mechanism, which has been loaded by initial movement of member 59 which has not as yet actuated on the valve. At this point however, the expansion of the spring 40 rapidly fires or accentuates the movement of member 59 causing it to have sudden impact with and rapidly to shift or reverse the fluid 45 controlling valve.

When the piston has reached its limit of stroke to the right, a similar action reversing 50 the valve will take place and the several parts will then be reshifted to the position as illustrated in Figure 4.

It will thus be seen that by supplying of a 55 constant volume to the pressure lines the mechanical or other limitation of movement of the grinding wheel spindle will cause a building up of the actuating pressure and when predetermined pressure has been built up the valve mechanism will automatically 60 reverse itself to cause a movement of the piston and parts controlled thereby in a reverse direction.

In the event that it is desired to stop oscillation of the spindle, use is made of the man- 65 ually controlled pressure relief valve 76.

This valve controls the pressure relief port 77 in communication with chamber 70 and is normally held closed as by the knurled thumb screw 78. When the screw is released to allow the valve to operate under its normal 70 spring pressure, the valve will keep a sufficient head of pressure in the system so that this pressure will shift and hold the spindle toward the right, but an insufficient head of pressure to cause a reversal of the valve 75 mechanism just described. The excess pressure will then flow through port 77 past valve 76 and be returned through passage 79 to the reservoir 18. When it is desired to 80 against start the oscillatory movement of the spindle it is merely necessary to hold valve 76 against its seat as by tightening of screw 78.

We claim:

1. A reciprocating mechanism for a grinding machine spindle or the like, including a non-rotatable oscillatable piston adjacent the spindle, means coupling the piston and spindle for joint oscillatory movement, a pump member contained within the piston, driving connections between the spindle and pump, and means for alternately directing the flow of the pump against opposite ends of the piston to cause reciprocation thereof. 85

2. An oscillating mechanism for the purpose described, including a reciprocable piston, a pump contained within the piston, a reversing valve contained within the piston for controlling the direction of flow from the pump, and means for actuating the pump. 95

3. In a machine of the character described, the combination with a spindle having an extension, of a piston cylinder circumscribing the extension, a piston movable within the cylinder, means for coupling the piston and extension for joint oscillatory movement, means securing the piston against rotation, a pump mechanism within the piston, means on the spindle for actuating the pump mechanism, and means within the piston unit for controlling the flow from the pump to the cylinder to vary the direction of movement of the piston. 100 105 110

4. A spindle oscillating unit, including a shiftable piston, contained fluid circulating means carried by the piston, and additional circulation varying means carried by the piston for controlling the direction of actuation thereof. 115

5. A device of the character described, including a fluid actuated oscillatable piston, a cylinder therefor, a series of fluid conduits, including means for alternately directing actuating fluid against opposite ends of the piston, a reversing valve, and connections between the actuating fluid conduits and the reversing valve for reversing the valve and directing the flow of the fluid to the opposite end of the cylinder when the built-up pressure 120 125 130

- in the receiving end of the cylinder exceeds a predetermined amount.
6. The combination with a grinding machine, including a rotatable spindle, of means for oscillating the spindle, including a pressure cylinder, a piston intermediately shiftable within the cylinder, means coupling the spindle and piston for joint oscillatory movement, a fluid circulating system, a reversing valve for directing the flow of fluid against either end of the piston as desired, a resilient valve firing mechanism, and a pressure connection for actuation of said mechanism when the pressure on the actuated end of the piston exceeds a prescribed amount.
7. The combination with an oscillatable machine tool spindle, of a piston coupled for reciprocation therewith, a fluid pressure pump actuated by rotation of the spindle, and a pressure operated automatic control mechanism for alternately directing the pressure against opposite ends of the piston for reciprocation thereof.
8. A machine tool spindle oscillating mechanism, including a piston coupled with the spindle, a fluid circulating system within the piston and a reversing valve within the piston for alternately directing the circulation to opposite ends of the piston for reciprocation thereof.
9. A machine tool spindle oscillating mechanism, including a piston coupled with the spindle, a fluid circulating system for fluid under pressure within the piston and a reversing valve within the piston for alternately directing the fluid under pressure to opposite ends of the piston for reciprocation thereof, said valve including an actuating member movable with and relative to the fluid reversing portions thereof, fluid pressure conduits forming a part of the circulating system and selectively directing pressure against the actuating member for causing such relative movement and additional mechanical means for effecting the joint movement of the parts.
10. A machine tool spindle controlling mechanism, including a reciprocable piston, a fluid circulation system for actuation of the piston, a pressure actuatable valve for reversing the system and adjustable means for reducing the resistance in one side of the system below the pressure required for actuation of the reversing mechanism.
11. A mechanism of the character described, including a cylinder, a piston oscillatable in the cylinder, a fluid pressure system having high and low pressure portions alternately couplable with opposite ends of the piston, a reversing valve controlling the coupling of the high and low pressure sides, connections between the valve and cylinder ends for actuation of the valve on excess of pressure in either end of the cylinder, and adjustable means for reducing the pressure in one end of the cylinder below an amount

necessary for actuation of the reversing valve.

12. An oscillating mechanism of the character described, including a cylinder and a piston shiftable within the cylinder, a pump mechanism contained within the piston for production of fluid pressure, means for continuously actuating the pump, a fluid supply in constant communication with the inlet side of the pump, a valve mechanism contained within the piston and having pressure inlet ports, exhaust ports, and additional ports communicating with opposite ends of the piston, and means controlled by the fluid pressure coupled with the valve mechanism for alternately connecting the ports at opposite ends of the piston with the pressure and relief ports.

13. The combination with a machine tool spindle having an axial extension, of an oscillating mechanism surrounding the extension and including a piston cylinder and a contained piston, means coupling the piston and spindle extension for joint axial movement, means securing the piston against rotary movement, a fluid circulating pump carried by the piston, means on the spindle for actuating the pump on rotation of the spindle, means for directing fluid under pressure into opposite ends of the cylinder, a reversing valve actuatable by said fluid under pressure for alternately directing the pressure to opposite ends of the cylinder and manually actuatable means for preventing reversal of the valve.

14. The combination with a machine tool spindle having an axial extension, of an oscillating mechanism surrounding the extension and including a piston cylinder and a contained piston, means coupling the piston and spindle extension for joint axial movement, means securing the piston against rotary movement, a fluid circulating pump carried by the piston, means on the spindle for actuating the pump on rotation of the spindle, means for directing fluid under pressure into opposite ends of the cylinder, a reversing valve actuatable by said fluid under pressure for alternately directing the pressure to opposite ends of the cylinder, and manually actuatable means remote from the valve for preventing actuation thereof.

15. The combination with a machine tool mechanism, of a self-contained oscillator therefor, including a reciprocable member, means carried by the member for generating an actuating force therein, and a self-contained reversing mechanism also carried by the oscillating device and operative on excess resistance to motion in a given direction to shift the device in a reverse direction.

16. A spindle oscillating mechanism for a machine tool, including a piston couplable with the spindle, fluid pressure means for actuating the piston, a reversing valve con-

- tralling the direction of actuation of the piston, means for adjustably limiting the movement of the piston in a given direction, and means operable by building up of pressure on limitation of the movement of the piston for reversing said valve. 5 70
17. A spindle oscillating mechanism for a machine tool, including a piston couplable with the spindle, fluid pressure means for actuating the piston, a reversing valve controlling the direction of actuation of the piston, means for adjustably limiting the movement of the piston in a given direction, means operable by building up of pressure on limitation of the movement of the piston for reversing said valve, a lost motion connection between said means and the valve, and a firing device cooperating with said lost motion connection for positive shifting of the reversing valve. 10 75
18. A spindle oscillating mechanism of the character described, including a piston, a spindle coupled with the piston for axial movement therewith and rotatable relative thereto, pressure creating mechanism associated with the spindle and operable on rotation thereof, means for selectively directing the pressure against opposite sides of the piston, means for limiting the movement of the piston in a given direction, and means controlled by the created pressure for reversing the actuation of the piston subsequent to said limitation of movement thereof. 15 80
19. A spindle oscillating mechanism of the character described, including a piston, a spindle coupled with the piston for axial movement therewith and rotatable relative thereto, pressure creating mechanism associated with the spindle and operable on rotation thereof, means for selectively directing the pressure against opposite sides of the piston, means for limiting the movement of the piston in a given direction, means controlled by the created pressure for reversing the actuation of the piston subsequent to said limitation of movement thereof, and manually operable means for rendering the pressure actuated reversing mechanism inoperative. 20 85
20. In a mechanism for oscillating a spindle, the combination with a spindle, of a piston operatively associated therewith, a pressure creating mechanism including a pump plunger, a cam on the spindle for actuating said plunger, a distributor valve for selectively directing the created pressure against either end of the piston, and a controller for the valve, comprising a supplemental piston coupled with the valve and operable by the actuating pressure, and means for selectively holding the controller inoperative against the pressure or accentuating the movement of the controller on building up of the pressure. 25 90
21. A control mechanism for a device of the character described, comprising a valve casting having a plurality of pressure inlet, out- 30
- let and exhaust ports, a slidable valve stem within the chamber having reversing valve portions for selectively coupling the outlet ports with either the pressure inlet or exhaust ports, supplemental pressure chambers within the casing and a valve shifting member having a lost motion connection with the valve stem and shiftable to form a closure for one or the other of the pressure chambers, and a spring detent normally holding the controller in position to close the pressure chamber, said controller and detent having cooperating portions for accentuating shifting movement of the controller when the latter is actuated by built up pressure in the chamber, whereby said accentuated movement will actuate the reversing valve. 35 95
22. A self-contained oscillating mechanism of the character described, including a reciprocable double end piston, a spindle to be oscillated, means coupling the piston with the spindle, a cylinder for the piston providing a pair of pressure chambers, a fluid chamber surrounding the piston intermediately of the length thereof, a pump contained within the piston and actuatable by rotation of the spindle, a connection from the inlet side of the pump to said fluid chamber, a distributor valve mechanism carried by the piston, discharge passages leading therefrom through the piston to the opposed pressure chambers, and means for shifting the distributor valve for regulating the flow of fluid from the pump to the pressure chambers. 40 1
23. A self-contained oscillating mechanism of the character described, including a reciprocable double end piston, a spindle to be oscillated, means coupling the piston with the spindle, a cylinder for the piston, providing a pair of pressure chambers, a fluid chamber surrounding the piston intermediately of the length thereof, a pump contained within the piston and actuatable by rotation of the spindle, a connection from the inlet side of the pump to said fluid chamber, a distributor valve mechanism carried by the piston, discharge passages leading therefrom through the piston to the opposed pressure chambers, an automatic reversing valve in the distributor for regulating the flow and discharge of fluid from the pump to the pressure chambers, and pressure actuatable mechanism in the controller chamber for operating the reversing valve. 45 1
24. The combination with a grinding machine having a spindle mounted for axial oscillatory movement, of means for controlling the movement of the spindle including a piston coupled therewith, a cylinder carried by the grinding machine and containing the piston, means for selectively directing fluid under pressure against opposite ends of the piston to cause reciprocation thereof, said means including a reversing valve actuatable by built up pressure in the piston cylinder. 50 1
- 60
- 65

der end to which actuating fluid is being supplied, and means for relieving said built up pressure to prevent actuation of the reversing valve thereby, whereby the piston and thus the spindle will be held against oscillatory movement.

In testimony whereof we affix our signatures.
